UNITED STATES PATENT OFFICE.

FREDERICK J. NUTTING, OF BROOKLYN, ASSIGNOR TO TRUSLOW & CO., OF NEW YORK, N. Y.

CORK-CUTTING MACHINE.

SPECIFICATION forming part of Letters Patent No. 295,884, dated March 25, 1884.

Application filed March 29, 1883. (No model.)

To all whom it may concern:

Be it known that I, FREDERICK J. NUTTING, of the city of Brooklyn, in the county of Kings and State of New York, have made certain new and useful Improvements in Cork-Cutting Machines; and I hereby declare that the following is a full and clear description of the same, reference being had to the accompanying drawings, in which—

10 Figure 1 is a side elevation of my cork-cutting device. Fig. 2 is a top view of the same. Fig. 3 is a view of the guide-wheel for the driving-belt. Fig. 4 is a view of the end of the pulley-wheel P, showing the stop-clutch. 15 Figs. 5, 6, 7, and 8 are views of the device for holding the cork-wood; and Fig. 9 is a sectional view, showing the central rod for expelling the cork from the cutter.

The object of my invention is to provide a 20 machine for cutting corks from cork-wood with a revolving cylindrical knife working at an incline and across the length of the bench on which it is placed, while at the same time the cork-wood is always automatically held firmly 25 in position when the knife enters it, and the motion or thrust of the cutting-knife may be governed and regulated by the foot of the operator.

In the drawings, A represents the bed-plate 30 or base upon which the cutting machinery rests, or to which it is secured. This bed-plate or base is firmly secured to a bench or table, B, by suitable supports, and arranged so that it will be at right angles to and across the 35 length of the bench and at an incline with the plane of the bench, as shown in the drawings, Fig. 1.

Secured to the bed-plate A are standards C C', which serve as supports and guides for a 40 knife-holding cylinder, D, which is revolved by a belt, E, passing around a driving-pulley, G, on a revolving shaft, T, and the pulley H on the cylinder D.

The cylindrical cutting-knife I is secured to 45 the cylinder D, and in front of it is arranged the mechanism for holding the strip of cork-wood during the operation of cutting the cork. The knife-carrying cylinder D is hollow throughout, and has secured to it at one end

the cylindrical knife or cutter I, and at the 50 other end has secured to it the two collars O O'. Projecting from the standard C, in a line with and below the knife-carrying cylinder D, is a rod or pin, J, sliding on which is a yoke, K, having arms N, which fit around the cylinder D, between the collars O O', and also gudgeons p p, by which the connecting-rod L is secured.

M is a crank-shaft, to which one end of the connecting-rod L is secured, and turns in bearings at the end of the bed-plate A. 60

P is a pulley, composed of the conical portion e, secured to and revolving with a shaft, Q, and the part d, which is loose and revolves freely on the shaft Q. The shaft Q is connected at one end to the crank-shaft M by a universal joint, R, as shown in Fig. 2, and is provided with suitable bearings, m and n. 65

S is a belt running over the pulley P and a pulley-wheel, U, on the revolving shaft T. 70

The shaft Q has its bearings m and n so arranged that it is set at an angle to the driving-shaft T and the crank-shaft M. This is done in order to bring the face of the cone-shaped portion of the pulley-wheel P about parallel with 75 the shaft T and the face of its pulley-wheel U, although I have found in practice that it is best to have the large end of the cone-shaped pulley slightly nearer the shaft T, in order to facilitate the working on it of the belt S. Secured to the frame-work of the base-plate A, and in front of the pulley P, is a guide, W, arranged to carry the sliding wheel Y, through which the belt S runs onto the pulley-wheel P. The position of the wheel Y is regulated 80 by the treadle or foot-lever Z, to which the wheel Y is connected by the cord X. The position and arrangement of the pulley P and belt S is such that the normal position of the belt is on the loose portion d of the pulley P, which draws upon the cord X and raises the treadle Z. On the end of the pulley P is secured a clutch or projection, o, which is reinforced by a spring, p', and sliding on the 85 guide W is a projecting arm, u, in position to engage the catch o when the belt is running on the loose wheel d, and instantly stop the revolutions of the shaft Q and the crank M,

so that the knife I will be stationary in a position where it is withdrawn from the cork-wood.

15 In front of the cutting-knife I is arranged a cutting-block, V, faced with lead or box-wood in the usual manner, and provided with an adjustable rest, r, for the strip of cork-wood s to rest upon.

Secured to the base-plate A in front of the 10 cutting-block is an adjustable slotted arm, H', and passing through it is a pin, v, to which the holders h h are secured. These holders h h each have a wing, i, set at an angle, as shown in Fig. 8, and are connected together by a bar, 15 w, about the base of the wings i i.

W is a rod passing loosely through the standards C and C', and extending far enough back of the standard C' to receive pressure from the yoke N at every forward thrust of the 20 knife-cylinder. The rod W is provided at its forward end with a catch-arm, z, which catches on the bar w, so as to keep the holders h h up in position against the cork-wood during the operation of cutting. The arm z is arranged 25 to slide on the end of the rod W, as shown in Fig. 5, being pivoted on a sliding block, y, resting on a spiral spring, x, which is designed to take up any excess of pressure from the action of the yoke N on the end of the rod W.

30 In order that the cork, when cut, may be thrust from the cylindrical knife, a central rod, D', passes through the knife-holding cylinder, and is secured by a bent arm, e, to the standard C'. This rod is not shown in Fig. 1, in 35 order to prevent confusion, but is represented in Fig. 9 with the cylindrical holder and knife in section.

In the operation of my improved machine, 40 the length of the knife being across the bench and on an incline instead of on a level with it, the operator has a better control over its operation, so that the work is greatly facilitated. In cutting corks a strip of cork-wood is placed in position on the adjustable rest r, and the 45 holders h h are brought up against it, sufficient pressure only being applied to keep the holders in an upright position and permit the strip of cork to be freely moved. When all is ready for cutting, the foot of the operator is 50 pressed upon the treadle Z, which will bring the belt S onto the conical pulley c and cause the cutting-knife I to be worked at a rate of speed which is governed by the pressure on the foot-lever or treadle Z, while both hands of 55 the operator are at liberty to manipulate the cork-wood in front of the knife. The holders h h are pressed firmly against the cork-wood each time the cutting-knife enters it, and the pressure is relieved when the knife is with- 60 drawn, so that the strip may be readily shifted and an uncut portion brought in front of the knife. The wings i i are arranged to effectually shield the hands of the operator from any accidental contact with the cutting-knife.

65 I do not herein claim, broadly, a cone-pulley the axis of which is at an angle to the axis of

the shaft of the companion pulley, nor a cone-pulley so arranged, in combination with a universal joint and a crank, as I hereby reserve the right to obtain a separate patent or patents for such subject-matter when considered apart from the particular machine herein described.

What I claim as my invention, and desire to secure by Letters Patent, is—

1. The combination, substantially as described, of a bench, a knife-cylinder arranged transversely to said bench and at an incline thereto, provided with a cylindrical knife, and means for imparting rotary and reciprocatory motion to said cylinder.

2. The combination, substantially as described, of a reciprocatory rotary knife-cylinder provided with a cylindrical knife, a cylindrical driving-pulley, a cone-pulley the shaft 85 of which is at an angle to the shaft of the driving-pulley, whereby the outer or belt-bearing face of the cone-pulley is parallel with the face of the cylindrical pulley, a belt stretched between said pulleys, and mechanism between 90 the shaft of said cone-pulley and said cylinder for converting the rotary motion of the former into the reciprocatory rotary motion of the latter.

3. The combination, substantially as described, of a reciprocatory knife-cylinder, a crank-shaft at a right angle thereto, means for connecting the crank of said shaft with said cylinder, a shaft arranged at an obtuse angle to said crank-shaft, a universal joint connecting 100 said shafts, and a cone-pulley on said inclined shaft, the belt-bearing face of which is parallel, or nearly so, with the face of the driving-pulley.

4. The combination, substantially as set 105 forth, of a reciprocatory knife-cylinder, a crank-shaft at an angle thereto, means for connecting the crank of said shaft with said cylinder, a shaft arranged at an obtuse angle to said crank-shaft, a universal joint connecting 110 said shafts, a cone-pulley on said inclined shaft, the belt-bearing surface of which is parallel, or nearly so, with the face of the driving-pulley, an adjustable belt-shifting pulley between said driving and cone pulleys, a treadle, 115 and means for connecting said belt-shifter therewith.

5. The combination, substantially as described, of a reciprocatory rotary knife-cylinder provided with a cylindrical knife, a crank-shaft, means for connecting the crank of said 120 shaft with said cylinder, a shaft at an obtuse angle to said crank-shaft, a universal joint connecting said shafts, a cone-pulley on said inclined shaft, provided with a spring-stop, and 125 a belt-shifting device provided with a stop, with which said spring-stop comes in contact.
